UNITED STATES PATENT OFFICE.

WILLIAM B. THIEMANN, OF ALBERT CITY, IOWA.

PORTABLE PNEUMATIC ELEVATING DEVICE.

Application filed October 17, 1922. Serial No. 595,104.

This invention relates to improvements in pneumatic elevating devices such as used in connection with ensilage cutters and the like and may be used for elevating ensilage or 5 grain, such as shelled corn or oats.

The object of my invention is to provide a pneumatic elevator of simple, durable and inexpensive construction which is adapted to be moved from place to place, and which 10 is easily and quickly placed into an operative position.

A further object is to provide in a portable pneumatic elevating device employing a centrifugal fan, improved means for feeding 15 material into the centrifugal fan in such a manner that a minimum amount of power is required to elevate the material at a given height.

A further object is to provide a pneumatic 20 elevator having a centrifugal blower so constructed that if a portion of the material should remain in the blower after it has become stopped, the centrifugal member may be operated and brought to its working velocity without slugging or clogging the same.

A still further object is to provide in a portable device having a pivoted receiving conveyor for feeding material to the elevating device, improved means for driving the 30 said auxiliary conveyor and for automatically throwing the same out of gear when the said portable elevator has been swung to a certain position of its movement.

These and other objects will be apparent 35 to those skilled in the art.

My invention consists in the construction, arrangement and combination of the various parts of the device, whereby the objects contemplated are attained, as hereinafter more 40 fully set forth, pointed out in my claims, and illustrated in the accompanying drawings, in which:

Figure 1 is an end elevation of my improved elevating device showing one of the 45 supporting wheels broken away and a portion of one of the frame members, for the purpose of illustrating other parts.

Figure 2 is an elevation of the right hand side of the device as shown in Figure 1.

50 Figure 3 is a detail sectional view of the blower casing taken on the line 3—3 of Figure 1.

Figure 4 is an enlarged detail sectional view showing the mechanism for driving the 55 auxiliary conveyor.

My improved elevating device is carried by a frame member 10 which comprises a set of horizontally arranged and parallel I beams 11, the back end of the said I beams being supported by a transverse member 12, 60 each of its ends being extended downwardly and outwardly to form a sort of brace and for supporting the members 11 at the proper height above the axle 13, the ends of the downwardly extending members being secured to the axle by means of bolts 14 extending through a series of holes 15 which provides means whereby the frame members 11 may be brought within a horizontal plane 65 even though the wheels 16 of the axle 13 rest 70 on uneven ground.

The forward ends of the members 11 are provided with a yoke 17, the said yoke having a vertically arranged shaft 18 rotatively mounted therein. The lower end of the shaft 75 18 is provided with downwardly extending fork members 19, the lower ends of each of the members 19 being provided with a slot 20 which is designed to receive an axle 21 supported by a wheel 22.

The axle 21 is adjustably connected with the lower ends of the members 19 by means of bolts 23. The upper end of the fork members 19 is provided with a series of holes 85 24 which are designed to receive a bolt 25 for the purpose of securing the tongue plates 26 in position, the plates 26 being mounted on a tongue 27 which is of the ordinary construction.

By this it will be seen that I have provided a supporting frame mounted on three wheels, one of which is pivoted in such a manner that the device may be easily and quickly moved from one position to another.

By providing three wheels I have overcome all twisting strain of the frame 10, and by providing a single pivoted wheel for steering the device I have provided means whereby the frame may be turned around in very small places, which is a very desirable 95 feature in devices of this kind.

Mounted adjacent to the inner face of each of the members 11 I have provided a disk 28 which forms the sides of the pneumatic blower. The disks 28 have three-fourths of 105 their periphery on the arc of a circle, and the other fourth rectangular, the ends of the circular portion of the periphery terminating in tangent lines intersecting at right angles to each other.

The periphery of the disks 28 are provided with a cylindrical plate 29 having its edges provided with flanges 30 for the purpose of receiving rivets 31, said rivets extending through the edge of the plates 28 and said flanges in such a manner that a substantially hollow cylindrical lower casing is formed. The top portion of the plate 29 is shorter than the top horizontal edge of the members 28 so as to form an opening 32 for the discharge of the material from within the blower casing.

The opening 32 is provided with a flange member 33 to which a short section of a tube 34 is secured by means of suitable rivets or bolts, the upper end of the tube 34 being provided with a flange 35 to which the ordinary blower pipe may be detachably secured.

20 Rotatively mounted centrally within the blower casing I have provided a fan 36 which is substantially of the ordinary construction, said fan being mounted on a shaft 37 which extends through the plates 28 and is rotatively mounted in suitable bearings 38 secured to the frame members 11. One end of the shaft 37 is provided with a belt pulley 39 by which the fan is driven from any convenient power.

30 One of the bearings 38 is provided with a gear casing 40 designed to receive a worm gear 41 secured to the outer end of the shaft 37.

Arranged above the shaft 37 and transversely therewith and within the casing 40 I have provided a shaft 42 which is designed to carry a worm gear 43 in mesh with the worm 41, one end of the shaft 42 being provided with a bearing member 44 secured to the frame 10. The opposite end of the shaft 42 is provided with a bearing 45 intermediate its ends.

The bearing member 45 has its outer face provided with a series of teeth 46 designed to be engaged by coacting teeth 47 of a rotary member 48 which is rotatively mounted on the shaft 42. The member 48 is provided with an arm 49 having a laterally extending portion 50.

50 The member 48 is designed to rotatively receive one end of a clutch sleeve member 51, the other end of which is provided with a series of teeth 52 designed to coact with a similar set of teeth in the hub 53 of a sprocket wheel 54, which is rotatively mounted on the outer end of the shaft 42, a collar 55 being provided to prevent the sprocket 54 from moving longitudinally with the shaft 42. A spring 56 is inserted between the hub 53 and the collar 51 so the teeth 52 and those of the hub 53 may be yieldingly separated.

In this connection it will be seen that if the lever 49 is rotated in a counter-clockwise direction, when viewed from the left hand

end of the shaft 42, as shown in Figure 4, the teeth 47 will be moved out of engagement with the outer end of the teeth 46 and allowed to enter between the said teeth 46. The spring 56 will then move the collar 51 70 and the clutch member 48 to the right, as shown in Figure 4, thereby causing the teeth 52 and the coacting teeth of the hub 53 to disengage each other, and the sprocket wheel 54 thrown out of gear with the shaft 42, the 75 collar 51 being rotated with the shaft 42 by means of the spline 57.

For feeding the material into the blower casing, I have provided an opening 58, in one of the plates 28. This opening is formed 80 preferably square or rectangular with its top edge below the shaft 37 and its lower edge above the bottom of the lower casing, the center of the opening being situated to one side of a vertical plane through the center 85 of the shaft 37, and toward the opposite side from which the opening 32 occurs, in such a manner that the vertical plane through the shaft 37 would pass substantially through the opening 58 a distance from the edge 90 closest to the opening 32 equal to one-third of the width or horizontal dimensions of the opening. These proportions can be slightly varied without materially effecting the operation of the device. I have found 95 by actual experiment that by locating the opening 58 at substantially this position, a larger amount of material will be delivered with a given amount of power than any other position in which it may enter the 100 blower casing.

Heretofore it has been common practice to provide the intake opening concentrically with the fan supporting shaft, but I find that a very large amount of power is required to operate the device when material is thus fed, due to the fact that the material thus fed goes into the opening concentrically with the center of the shaft, and the suction created by the same draws the material 105 through the opening. The material is then delivered in all directions to the outer plate 29 by centrifugal force. That is, part of the material would be thrown upwardly 110 against the top portion, part of it against the side portions and part of it against the bottom portions of the plate 29.

All of the material that is thrown to the top portion, when the fan is driven in a counter-clockwise direction, as shown in Figure 3, will be dragging against the plate 29 from the point A to the point B, at which time it will then be delivered upwardly to the opening 32. Not only does the material 115 drag against the plate 29, but also has a tendency to bind and clog between the outer edges of the fan blades and the said plate, thereby increasing the amount of power required to discharge the material due to the 120 excessive friction.

I find that when material is delivered through an opening located as illustrated in the drawings that the material is delivered into the casing between the fan blades. As 5 the material is moving inwardly, it is moving in a path transverse with the movement of the fan blades.

On account of the rapid movement of the said blades, a large amount of material is 10 actually engaged by the said blades before it has even fallen to the plate 29, the inertia of the material causing it to engage the fan blades until the blades have traveled through an angle of about ninety degrees, or until they have reached the point B. The centrifugal force by this time is moving the material toward the outer edges of the fan blades. As it will be seen, it is not only moved outwardly, but it is thrown 20 directly upwardly through the opening 32. In other words, the fan acts on the impact principle as well as the principle of centrifugal force.

By providing the end of the top of the plate 29 horizontal or in a plane at right angles to the vertical portion of the plate 29 instead of bringing the end of the top portion of the plate on a curve, as is the usual practice, I have eliminated the clogging and 25 slugging of the material at this point, which has heretofore been a serious objection in devices of this kind.

Heretofore it has been necessary to operate the fan until all of the material has been 30 discharged from the blower casing. Otherwise, when it is desired to start the fan in operation, the material within the bottom of the casing will follow the fan blades around, and the centrifugal force not being sufficient 35 to discharge the material upwardly through the outer end of the discharge pipe, it would fall back, collect and gather at the point C, as ordinarily constructed.

By providing the end of the upper portion of the plate at right angles to the vertical portion of the plate 29, I have largely 40 eliminated this difficulty, as this provides plenty of room at this point where the material may fall back over the outer edges of the fan blades or between them toward the center of the shaft 37.

For discharging material into the opening 55 58, I have provided a conveyor 59 mounted in a trough 60, the said trough being designed to lie, when in an operative position, horizontal and on the ground surface. The arrangement of this trough, however, is common in other devices of this character.

The inner end of the trough 60 is pivoted 60 to downwardly extending frame members 61 secured adjacent to each side of the opening 58, by means of a shaft 62.

One end of the shaft 62 is provided with a 65 sprocket wheel 63 in line with the sprocket wheel 54. The sprocket wheels 54 and 63

are provided with a chain 64. The shaft 62 is operatively connected with a conveyor 59 in the usual manner.

By pivoting the trough 60 to the member 61, I have provided means whereby the said 70 trough may be moved to a vertical position for the purpose of permitting loaded wagons to be driven adjacent to the side of the blower, after which the trough is lowered to its horizontal position back of the loaded 75 wagon to receive the material from the wagon box.

In the side members 65 of the trough 60 I have provided notches 66 for the purpose of permitting the said trough to assume a vertical position without engaging the conveyor driving mechanism, as shown in dotted lines in Figure 1. Each side of the opening 58 is provided with side plates 67 which are for the purpose of covering the notches 66 and 80 preventing the material from being discharged through the said notches as it is delivered to the opening 58.

When the trough 60 is moved to its vertical position, the conveyor member 59 is in 90 such position that it will engage the box-ing member 40 and would be broken unless means was provided for automatically throwing the conveyor out of gear. For this purpose I have provided the members 95 49 and 50 and the clutch device operated thereby, as before described.

It will be seen that as the trough is moved to a vertical position that the upper edge of one of the members 65 will engage the member 50 and move it in such position as will effect the spring 56 and hence throw the sprocket 54 out of operative relation with the shaft 42, and thereby provide means for automatically throwing the conveyor out of gear.

The device may be thrown in gear by moving the member 50 outwardly. This provides means for manually throwing the conveyor 59 into and out of gear at the 110 will of the operator.

Thus it will be seen that I have provided a pneumatic elevator or blower of comparatively simple, durable and inexpensive construction which may be easily moved from 115 one position to another, and which requires a minimum amount of power for its operation, and also being provided with means whereby it will not slug or clog up easily.

The device may be used for elevating the 120 various kinds of materials, such as small grain, shelled corn or ensilage, and is particularly designed to be used for the purpose of elevating ensilage into silos to be used in connection with that type of an 125 ensilage harvester which harvests and cuts the ensilage in the field.

I claim as my invention:

1. In a device of the class described, a cylindrical blower casing, a drive shaft pass-

- ing through said casing, a fan on said drive shaft, a drive pulley on one end of said drive shaft, a second shaft arranged transversely to the other end of said drive shaft, means for imparting movement from said drive shaft to said transversely arranged shaft, a sprocket wheel rotatively mounted on one end of said transverse shaft, said sprocket wheel including a clutch member, 5 a second clutch member slidably mounted on said transverse shaft designed to coact with the first said clutch member, means for yieldingly holding said clutch members normally in contact, a rotatable member mounted on said transverse shaft for moving said second clutch member out of engagement with said first clutch member, an arm mounted on said rotatable member, a second transverse shaft parallel with said transverse shaft, a conveyor pivotally mounted on said second transverse shaft and capable of movement from a horizontal to a vertical position, a sprocket wheel mounted on one end of said second transverse shaft, a chain for said sprocket wheels, 60 and said members being so arranged that when the conveyor is moved from a horizontal to a vertical position the operation of the said conveyor is stopped.
- 10 3. In a device of the class described, a blower including a fan, means for operating said fan, a conveyor for feeding material to the said blower, said conveyor having one end pivoted and designed to swing from a horizontal to a vertical position, 70 means for operating said conveyor, driven from said fan operating means, said last means including a hand-actuated clutch for throwing the conveyor into and out of operation, said conveyor and said clutch being 75 so located that when the conveyor is moved to a vertical position the clutch will automatically throw the conveyor out of operation.
- 15 4. In a device of the class described, a cylindrical blower casing, said casing being provided with a discharge opening and an intake opening mounted in one end of the casing between its center and its periphery, 80 a drive shaft passing through said casing, a fan on said drive shaft, a drive pulley on one end of said drive shaft, a second shaft arranged transversely to the other end of said drive shaft and above said intake opening, means for imparting movement from 85 said drive shaft to said transversely arranged shaft, a sprocket wheel rotatively mounted on one end of said transverse shaft, said sprocket wheel including a clutch member, a second clutch member slidably mounted on said transverse shaft designed to coact with the first said clutch member, means for yieldingly holding said clutch members normally in contact, a rotative member 90
